UNITED STATES PATENT OFFICE.

EDWARD WYLDE OF NEW YORK AND THOMAS BRADY, OF YONKERS, NEW YORK

LUBRICATING DEVICE.

1,411,654.

Specification of Letters Patent.

Patented Apr. 4, 1922.

Application filed August 9, 1916, Serial No. 113,850. Renewed July 27, 1920. Serial No. 399,440.

To all whom it may concern:

Be it known that we, EDWARD WYLDE and THOMAS BRADY, citizens of the United States, residing at New York, N. Y., and Yonkers, 5 New York, respectively, have invented certain new and useful Improvements in Lubricating Devices, of which the following is a clear, full, and exact description.

This invention relates to lubricating devices, and particularly to lubricating devices 10 which are especially adapted for lubricating the guide rails of elevators and the like.

An object of the invention is to provide improved lubricating means which will automatically supply to the relatively movable parts with which it is associated, enough lubricant to insure effective lubrication, but will not supply too much lubricant and will not cause a waste of the lubricant.

More particularly the invention aims to 20 provide lubricating means for elevator guide rails and the like, which may be mounted on the elevator car and carried therewith and operated in such manner that it will 25 lubricate the guide rails proportionately to the travel of the car thereover. The invention aims further to provide an automatic lubricating device which will handle lubricant in liquid form without waste, 30 either through excessive application of the lubricant to the part to be lubricated, or through leakage or spilling from the lubricating means itself.

Important features of the invention are 35 the novel wiping means for applying the lubricant to the rail or other part to be lubricated, the novel means for supplying lubricant to the wiping means, the means for adjusting the lubricant supplying means to 40 vary the amount of lubricant supplied at a single operation, the construction and arrangement of the lubricant reservoir and wiping means so that lubricant supplied to

ing description and claims when considered in connection with the accompanying drawings in which

Fig. 1 is a perspective view of a lubricating device embodying the invention, parts being broken away to show parts otherwise concealed;

Fig. 2 is a bottom plan view of the wiping means and the holder therefor; and

Fig. 3 is a perspective detail showing the construction of the interior of the support for the wiping means.

The illustrated lubricating device which is adapted to be carried upon the top of an 70 elevator car, preferably above the guide shoe which embraces the rail, comprises a reservoir 2 for the lubricant, said reservoir having lugs 4 by which it may be attached to the car. Projecting to one side of the reservoir and near its upper end is the support 6 for the wiping means by which the lubricant is applied to the elevator rail 8, shown in dotted lines and also partly broken away. The support 6 is preferably integral with 75 the reservoir 2 and comprises a chamber having a slot or guide in which the rail is received and in which the rail comes into contact with the wiping means confined in said chamber. A common cover 10 is adapted to cover both the lubricant reservoir 2 and the support 6 for the wiping means.

The illustrated wiping means comprises a pad 12 of felt or other suitable absorbent material confined between upper and lower 90 holding members 14 and 16 respectively, this pad being provided with a slot to receive the elevator guide rail and also being cut in at 18 to permit the pad to adjust itself readily to the rail. The holding members 14 and 16 95 protect the wiping means from wear without in any way interfering with its wiping action, and may be of any suitable material such as vulcanized fibre. There are pref-

ervoir, and conduit means leading into the reservoir to convey thereto any excess lubricant.

14. In a lubricating device, in combination, a lubricant reservoir, wiping means for applying the lubricant to the part to be lubricated, means for supporting said wiping means at a level above the lubricant in the reservoir, the bottom of said supporting means having a rim engaging the bottom edges of the wiping means adjacent the part to be lubricated, supports for said wiping means spaced from the bottom of said chamber, said bottom sloping towards the reservoir, conduit means leading into the reservoir to convey thereto all excess lubricant, and means for preventing filling of the reservoir above the level of said conduit means.

15. In a lubricating device for elevator rails and the like, in combination wiping means comprising absorbent material shaped to embrace three sides of the rail to be lubricated, a divided holder confining the sides of the wiping face of said absorbent material, a casing supporting said holder, and means yieldingly pressing the holder

towards the rail arranged to maintain said absorbent material yieldingly in contact with all three sides thereof, said means comprising springs engaging said divided holder and camming faces forming part of said casing.

16. In a lubricating device for elevator rails and the like, in combination, wiping means comprising absorbent material shaped to embrace three sides of the rail to be lubricated, a divided holder confining the sides of the wiping face of said absorbent material, a casing for said holder, springs between the holder and casing so constructed and arranged as to hold said holder in said casing, and to exert pressure on said absorbent material to yieldingly maintain it in contact with all three sides of the rail.

Signed at Hoboken, N. J., this 7th day of 45
August, 1916.
